UNITED STATES PATENT OFFICE

147,732

DESIGN FOR A COMBINED BOTTLE OPENER AND ICE PICK

Harry Lachman, Beverly Hills, Calif.

Application May 13, 1946, Serial No. 129,663

Term of patent 3½ years

(Cl. D44—29)

To all whom it may concern:

Be it known that I, Harry Lachman, a citizen of the United States, residing at Beverly Hills, county of Los Angeles, State of California, have invented a new, original, and ornamental Design for a Combined Bottle Opener and Ice Pick, of which the following is a specification, reference being had to the accompanying drawing, forming a part thereof.

I claim:

The ornamental design for a combined bottle opener and ice pick, as shown.

HARRY LACHMAN.
